UNITED STATES PATENT OFFICE

150,136

DESIGN FOR A COMBINATION TELEVISION
LENS AND MOUNTING MEANS THEREFOR

Jack F. Hecht, Chicago, Ill.

Application December 2, 1947, Serial No. 142,915

Term of patent 14 years

(Cl. D61—1)

To all whom it may concern:

Be it known that I, Jack F. Hecht, a citizen of the United States, residing at Chicago, in the county of Cook and State of Illinois, have invented a new, original, and ornamental Design for a Combination Television Lens and Mounting Means Therefor, of which the following is a specification, reference being had to the accompanying drawings, forming a part thereof.

In the drawings:

Fig. 1 is a top plan view of a combination television lens and mounting means therefor, showing my new design; Fig. 2 is a front elevation of the same; and Fig. 3 is a side elevational view thereof.

The lens is adapted to magnify images appearing on a television screen, and is correspond-

ingly larger than the screen with which it is associated.

I claim:

The ornamental design for a combination television lens and mounting means therefor, as shown and described.

JACK F. HECHT.
